UNITED STATES PATENT OFFICE.

JOHN H. KOLB, OF BROOKLYN, ASSIGNOR OF ONE-THIRD TO WILLIAM J. MATHESON, OF NEW YORK, N. Y.

METHOD OF AND APPARATUS FOR CONCENTRATING METALLIC AND OTHER SALTS.

SPECIFICATION forming part of Letters Patent No. 308,903, dated December 9, 1884.

Application filed July 25, 1884. (No model.)

To all whom it may concern:

Be it known that I, JOHN H. KOLB, a citizen of the United States, residing in the city of Brooklyn, county of Kings, and State of New York, have invented a new and useful Method of and Apparatus for Concentrating Metallic and other Salts, of which the following is a full, clear, and accurate description.

In the way that such salts are now usually concentrated they are extremely liable to become destroyed by reason of the high heat necessarily used and by the manner in which the heat is applied. The salts in solution are usually placed in a vessel and heat applied to the bottom thereof, the consequence of which is that, the heat acting unequally on the bottom of the vessel, the bottom portion of the solution first becomes concentrated, and, resting on the bottom, is spoiled by the heat before the top or middle portion of the solution is properly acted upon.

My invention has for its object an equal and uniform distribution of the heat to the solution containing the salts, in order to concentrate all portions of the solution at the same time.

My method consists in applying to the pan or concentrator holding the saline solution to be concentrated means whereby heat is applied equally to the top surface of the solution and of said pan; and the apparatus to be used for this purpose consists of a pan or concentrator having an outside water-jacket or other protection through which water can circulate, and which outside covering or water-jacket can be attached at will to a water-supply of sufficient pressure to cause the water to circulate therein, the whole movable, and to be used in connection with a reverberatory or other suitable furnace.

In applying my invention I take a pan of suitable dimensions to contain the amount of solution to be concentrated and affix to the outer sides thereof a protection or jacket provided with means whereby water can be introduced into and discharged therefrom at will. The pan is then mounted upon a truck, and when filled with the solution to be concentrated is pushed into a reverberatory or other furnace. The connections are then made between the source of water supply and the jacket

and discharge-pipe, and the water allowed to circulate through the jacket. The flame of the furnace is thrown onto the top surface of the solution, and the sides of the containing-pan are kept from being warped and injured by the heat, and the solution is evenly concentrated without danger of any portions thereof caking or burning on the sides or bottom of the pan.

In the drawings, Figure 1 shows my concentrator and the form of connection with the solution to be concentrated which I prefer. Fig. 2 shows the connection of the water-supply with the water-jacket. Fig. 3 shows a sectional view of the pan and water-jacket.

A represents a reservoir placed at a convenient distance above the pan, and filled with the liquid or solution to be concentrated.

B is a pipe leading from the reservoir down to the containing-pan. This pipe B is provided with the stop-cock b, by which the solution can be turned on so as to flow down when desired, or the supply turned off when desired.

C is the containing-pan or other receptacle, of suitable dimensions, mounted on a truck, D, the wheels of which run on a truck or slide.

E is the reverberatory furnace. The pan C is surrounded by a water-jacket, H, through which a constant supply of water circulates. The water-jacket H is provided with a discharge, h. The water is supplied from a reservoir, G, (see Fig. 2,) which is connected with a source of water-supply by the water-pipe I.

Attached to the lower end of the reservoir G is the pipe O, connected with which is the flexible hose or pipe P, the end of which is placed in the water-jacket H.

The reservoir G and pipe I are provided with a ball-cock, R, which floats in the water of the reservoir, and by its action automatically regulates the supply of water passing through the pipe O and flexible connection P to water-jacket H, and keeps the water-supply at a constant pressure.

The operation of my invention is as follows: The pan C and water-jacket H, mounted on the truck D, are moved into the furnace E on the truck or slide in the furnace to a suitable position under the pipe B, connecting with the reservoir A, containing the solution to be con-

centrated. The water-jacket is connected by means of the flexible hose or connection P and pipe O with the water-reservoir G. The stop-cock b is then turned and a sufficient supply 5 of solution let into the pan. When sufficient quantity of solution to be concentrated has entered the pan C, the stop-cock b is turned and the supply of solution cut off. As the solution is concentrated, the water-jacket H, being 10 constantly fed with a supply of water, prevents the sides of the containing-pan C from being impaired by the flame of the furnace, and the solution is evenly concentrated, and no portion of the solution is caked or burned. 15 When the salts are sufficiently concentrated, the jacket is disconnected from the water-pipes, the truck removed from the furnace, and the pan is emptied.

Having thus described my invention, what I 20 claim, and desire to secure by Letters Patent, is—

1. An apparatus for concentrating metallic salts or other substances, consisting of a pan or concentrator holding the solution to be concentrated, an outside water-jacket or other protection through which water can circulate, and which outside jacket or covering can be attached at will to a water-supply of sufficient pressure to cause the water to circulate therein, the pan and water-jacket being movable and used in connection with a reverberatory or other suitable furnace.

2. An apparatus for concentrating metallic salts or other substances, consisting of a pan 35 or concentrator connected by a pipe or other suitable connection with a reservoir holding

the solution to be concentrated, a water-jacket or other protection surrounding said pan, through which water can circulate, which water-jacket or other protection can be attached at will to a water-supply of sufficient pressure to cause the water to circulate therein, the pan or concentrator and water-jacket or other protection being mounted on a suitable truck running on a track or slide, the top 40 surface of the solution in said pan being subjected to the heat of a reverberatory or other suitable furnace.

3. An apparatus for concentrating metallic salts or other substances, consisting of a pan 45 or concentrator connected by a pipe or other suitable connection with a reservoir holding the solution to be concentrated, a water-jacket or other protection surrounding said pan, through which water can circulate, which 50 water-jacket or other protection can be attached at will by pipes or other suitable connections with a reservoir holding water, the supply of which water to said water-jacket is automatically regulated and kept at a constant pressure, such pan or concentrator and water-jacket or other protection being mounted on a suitable truck moving on a track or slide, the top 55 surface of the solution in said pan being subjected to the heat of a reverberatory or other furnace.

In testimony whereof I have hereunto set my hand this 15th day of July, 1884.

JOHN H. KOLB.

In presence of—

WILLIAM ARCHER,

W. WALLACE URQUHART, Jr.
